UNITED STATES PATENT OFFICE.

EUGENE S. RICE AND GABRIEL E. BAILLY, OF LAKE ARTHUR, LOUISIANA.

BLOTTER ATTACHMENT.

1,091,535.

Specification of Letters Patent. Patented Mar. 31, 1914.

Application filed April 24, 1913. Serial No. 763,457.

To all whom it may concern:

Be it known that we, EUGENE S. RICE and GABRIEL E. BAILLY, citizens of the United States, residing at Lake Arthur, in the parish of Calcasieu, State of Louisiana, have invented certain new and useful Improvements in Blotter Attachments; and we do hereby declare the following to be a full, clear, and exact description of the invention, such as will enable others skilled in the art to which it appertains to make and use the same.

This invention relates to stationery appliances, and it more particularly relates to an improved form of blotter holder.

An object of the invention is to provide an improved blotter attachment whereby the blotter may be quickly and easily secured on the wrist of an operator.

Another object of the invention is to provide a device of this character which may be quickly and easily removed from an old blotter and attached to a new one.

Another object is to provide an attachment of this character which may be employed in connection with any blotter of ordinary character or construction.

Another object is to provide an attachment of this character which may be quickly, easily and accurately adjusted to wrists of different sizes.

Another object is to provide a device of this character which is comfortable and convenient for the user.

Another object of the invention is to provide a device of this character which is simple of construction, light, neat, and comparatively inexpensive.

Another object is to provide a device of this character which is especially adapted for advertising purposes.

Other objects and advantages may be recited hereinafter and in the claim.

In the accompanying drawings, which supplement this specification; Figure 1 is a perspective view of a hand and wrist having our improved blotter attachment employed in holding a blotter thereon. Fig. 2 is a rear elevation view of our improved blotter attachment secured to a blotter. Fig. 3 is an enlarged top plan view of our improved blotter attachment disconnected from the blotter on which it rests, and Fig. 4 is a bottom plan view of a section of a blotter having our improved blotter attachment secured in place.

Referring to the drawings, in which similar reference characters correspond with similar parts throughout the several views, the strip 5 of elastic material constitutes the principal element of our invention, and may be of solid rubber, or of fabric and rubber, being preferably flat, and adapted to have advertising matter printed thereon. A snap element 6 having a knob 7 thereon is secured on one end of the element 5 and is adapted to engage with a second snap element 8, which latter is provided with a spring 9, adapted to engage with the knob 7. A neck 10 connects the knob 7 with the disk which comprises the base of the snap element 6, and this head 7 is adapted to be forced through an ordinary blotter, so that the neck 10 extends through the aperture made by the head, and the snap element 8 is then forced into engagement with said head, for holding the blotter securely in engagement with the end of the strip 5 to which the snap element 6 is secured. The opposite end of the strip 5 is preferably hemmed at 11, and the adjacent end portion is passed through an apertured plate or hook element 12 having a hook 13 formed thereon. This hook may be stamped from sheet metal, and made of pliable material, so that the hook may be alternately bent back and forth, for quickly forcing it through a blotter and then clenching it upon the blotter; but, in practice, pliable material need not be employed when suitable apertures have been previously formed in the blotter, and the hooks may be formed rigidly and of any suitable shape for effecting easy and secure engagement with the blotters. The thickness of the material is so slight that the hook may be easily bent by the fingers of an operator or user without the use of tools. The end portion 14 of the tape is bent or folded back upon the medial portion of the strip and engages with a friction plate 15, which is apertured at 16 and provided with a bridge 17 between the apertures. The end portion 14 and medial portion of the strip 5 pass through the apertures 16, and are slightly curved where they pass around the bridge 17, so that said end portion has frictional engagement with said medial portion, and also with said bridge, while said medial portion has frictional engagement with the side bars of the plate 15.

It will be seen, that in order to adjust the length of the strip 5, it is only necessary to

increase the length of the portion 14 between the seam 11 and the point where the strip passes through the plate 12, and then to adjust the plate 15 on the strip 5, for holding said strip in its adjusted position.

In practice, the blotters 18 are manufactured of a suitable size and with properly located apertures of triangular or other proper shape through which the fastening devices 10 may be inserted and secured; but, in the event that the user's supply of such blotters become exhausted, he may easily prepare, attach and use any ordinary blotter.

In operation, the user having first selected or obtained a piece of blotter of the desired size, the hook 13 is then passed through or engaged with one of the apertures through the blotter, or else forced through an edge portion of said blotter and clenched or otherwise secured. The blotter is then placed upon the palm of the hand, so that its rear end overlaps the wrist, and the tape 5 is then placed around the wrist, and adjusted, as previously described, to fit the wrist. The knob 7 is then pressed through the blotter, and the snap element 8 is quickly secured in place thereon, whereupon, the writer may quickly blot the matter which he has written, and proceed to alternately write and blot, without the necessity of looking each time for a blotter.

This device is especially useful in addressing envelopes, cards, etc., where haste is required and where the cards or envelopes are to be piled in superposed relation, and it will be seen that its use will result in a great saving of time and in avoiding much un-

sightly smearing of ink upon the finished work. This device will also be found especially useful in bookkeeping, as the bookkeeper may quickly blot his figures, and immediately turn his pages without danger of smearing the same.

It will be seen that we have provided a device of this character which is fully capable of attaining the foregoing objects, in a thoroughly practical and efficient manner.

We do not limit our invention to the exact details of construction, combinations and arrangements of parts, herewith illustrated and described, but our invention may only be limited by a reasonable interpretation of the claim.

We claim:

The combination with a blotter sheet, of a band having a hook at one end engaged through one edge portion of the blotter sheet, a plate secured to the other end of the band and having a stud formed thereon with an enlarged head, and engaged through the opposite edge portion of the blotter sheet, and a socket member receiving the stud and having a flat face engaged against the opposite side of the blotter sheet whereby said blotter sheet will be clamped between the flat faces of the plate and socket member.

In testimony whereof, we affix our signatures, in the presence of two witnesses.

EUGENE S. RICE.
GABRIEL E. BAILLY.
